UNITED STATES PATENT OFFICE.

CHARLES M. BRANDT, OF PHILADELPHIA, PENNSYLVANIA.

SAFETY-GUARD FOR PRESSES.

1,234,723.

Specification of Letters Patent.

Patented July 31, 1917.

Application filed December 1, 1915. Serial No. 64,500.

To all whom it may concern:

Be it known that I, CHARLES M. BRANDT, a citizen of the United States, residing at Philadelphia, in the county of Philadelphia and State of Pennsylvania, have invented new and useful Improvements in Safety-Guards for Presses, of which the following is a specification.

The invention relates to presses and has 10 for an object to provide a guard for preventing injury to the operator of the press.

A still further object of the invention is the provision of a device, which aside from 15 acting as a guard or safety apparatus for the operator of a printing press also prevents the stacked printed matter on the table from falling into the press in cases where the jarring of the table causes the stacked matter to fall, or when the printed matter 20 slips out of the hand of the operator while being removed from the platen.

The invention is particularly adapted to printing presses and the like and primarily to the bed and platen type of press, to the 25 end that the hand of the operator will be prevented from becoming wedged or mashed between the chase and platen, upon movement of the latter into closed or printing position.

30 It is well known that a large number of injuries occur annually, due to the failure of the operator of a press such as mentioned, to remove his or her hand from the platen after placing the blank matter to be printed, thereon, and in which instance the hand, projecting across the face of the platen, is wedged and mashed between the platen and chase as the latter moves toward the chase or vice versa. Injuries of this 35 character occur mostly on printing presses having a slow opening and quick closing movement or when both the chase and platen are moved toward each other.

With the avoidance of these injuries in 40 view, I provide a simple, inexpensive guard, operating in conjunction with the press to remove the hand of the operator from the platen of the press and out of the way of the danger zone mentioned, when the platen 45 is moving toward printing position.

In the further disclosure of the invention reference is to be had to the accompanying drawings, constituting a part of this specification, in which similar characters of ref-

erence denote corresponding parts in all the 55 views, and in which:

Figure 1 is a fragmentary side elevation of a press, showing my device applied thereto and in guarding position,

Fig. 2 is another fragmentary side elevation showing the press with the device in 60 inoperative or normal position, the platen being in open position relative to the bed of the press,

Fig. 3 is a perspective view of the bracket 65 and cam,

Fig. 4 is a perspective view of the guard proper, with the curtain broken away.

Fig. 5 is a perspective view of the guide, and

Fig. 6 is a vertical transverse section 70 taken through one of the extensions of the U-shaped element, showing the application of a roller thereto.

Referring more particularly to the views 75 I disclose a printing press 10, of the bed and platen type, the essential parts as shown being the frame 11, swinging platen 12, table 13 and bed 14 with the usual chase 15 carried in the bed.

Secured to the back of the platen 12 on each side is a guide bracket 16, preferably 80 consisting of spaced plates 17 and guides 18, the guides being fitted snugly against the back of the platen as will be clearly seen. 85 Set screws 20 passing through one of the plates 17 engage a face of a flange 21 on the platen, with the other plate 17 abutting against the underside of the flange, thus rigidly holding the guide bracket against 90 movement.

A substantially inverted U shaped element 22, constitutes the guard proper and as shown is preferably formed of a single 95 piece of metal, bent in the shape mentioned, and formed with lateral extensions 23 having rollers 24 journaled thereon. The element 22 is arranged to slide in the guides 18, being thus arranged and movably supported in the rear of the platen.

Secured to each side of the frame 11 of the press is a bracket 25, preferably formed to provide a forwardly projecting cam 26 and a rearwardly projecting arm 27 terminating in a tubular bearing 28. Referring care- 100 fully to the views it will be seen that the extensions 23 of the element 22 pass through the irregular openings 29 of the cams thus

causing the rollers 24 to coöperate with the cams. An apron 30 has a loop 31 at each end with a rod 32 passing through one loop with its ends seated in the bearings 28 of the brackets 25, the straight portion 33 of the element 22 being passed through the other loop of the apron.

Attention is particularly directed to the cams 26 of the brackets, and referring to Fig. 2 it will be seen that when the platen is in open position to receive matter to be printed, the straight portion 33 of the element 22 will lie substantially flush with the upper edge of the platen. Now as the platen swings forwardly and downwardly to bring the matter to be printed, toward the form, the hand of the operator, used to place the matter on the platen would become wedged between the platen and the form if not withdrawn. Therefore as the platen moves into the position last mentioned it will be seen that at a certain moment, and due to the novel construction of the cams, the element 22 will be raised on the platen so that its straight portion, coming up beyond the edge of the platen, will bear against the hand of the operator and force it from the dangerous position, between the platen and form. With this construction it will therefore be seen that each time the platen moves into position for printing the movement of the element 22 will serve as a warning to the operator and the element striking the hand of the operator will throw it or the fingers out from between the platen and form. As the platen returns to open position the element 22, having the extensions 23 and rollers 24 loose in the openings of the cams, will gravitate in the guides, and also, due to the formation of the cams, be pulled into normal position, the straight portion 33 being now again substantially flush with the edge of the platen.

It will also be noted that the apron 30 pulled taut when the guard element is raised prevents the operator's hands from being advanced into the machine beneath or in back of the platen, and where they would be crushed upon the return of the platen to a normal position.

Frequently a card, envelop or some other printed matter, falls into the working mechanism of a press and the operator in a vain attempt to catch the falling card has his or her hand crushed in the press. With the addition of the apron, however, the usual openings in the frame of the press, in front of the table, are covered and thus the operator cannot insert the hands. Aside from this, however, the apron is of vast importance, in that it prevents printed matter that slips from the operator's hand, from falling into the mechanism of the press, and furthermore when stacked printed matter in the press falls over, as is oftentimes the case, due to the jarring of the table, the apron here also,

will prevent the falling cards, envelops or the like from lodging in the press and thus hamper the proper working thereof.

Although I am aware that safety devices have been used heretofore for presses, my device in its simplicity presents various features of commercial value, as for instance, in the application of the device to the press. Consisting merely of the cam brackets, guide brackets, guard element and apron, it will be clear that one not skilled in the art can readily attach the simple structure to the press with the aid of a simple form of wrench. Furthermore, in the operation of the device, the construction of the cams and the use of the same with the remaining structure, accomplish a result, that ordinarily is not attained, namely a quick and positive raising of the guard element into accident preventing position just before the otherwise critical moment when the hand or fingers of the operator would be endangered. By having this action of the guard element positive and abrupt, the operator is both warned and operated upon by the element striking the hand. It should be carefully noted that the movement of the guard element into safety position pulls the apron taut so that the operation of the two is almost simultaneous and positive, the return of the guard element to normal position and the slackening of the apron as shown in Fig. 2 being also substantially simultaneous.

Having described my invention, I claim:

1. In a printing press guard, the combination with a form and a platen movable toward and away from said form, of a guard carried by said platen and movable upwardly from the platen in the movement of the latter toward the form and embodying a frame having lateral extensions thereon, and brackets rigidly attached to the frame of the printing press and embodying arms formed with cam-shaped openings to receive said lateral extensions, whereby in the movement of the platen toward the form said lateral extensions engage in said openings and slide said frame upwardly.

2. In a printing press guard, the combination with a form and a platen movable toward and away from said form, of a guard carried by said platen and movable upwardly from the platen in the movement of the latter toward the form and embodying a frame having lateral extensions thereon, brackets rigidly attached to the frame of the printing press and embodying arms formed with cam-shaped openings to receive said lateral extensions, whereby in the movement of the platen toward the form said lateral extensions engage in said openings and slide said frame upwardly, arms projecting rearwardly from said brackets, respectively, and a flexible sheet having one edge connected to the rear edges of said arms and the other

edge connected to said guard and adapted to be drawn taut in the movement of the platen toward the form.

3. In a printing press guard, the combination with a form and a platen movable toward and away from said form, of a guard carried by said platen and movable upwardly from the platen in the movement of the latter toward the form and embodying 10 an inverted U-shaped frame, guide tubes detachably connected to the platen and encir-

cling the legs of the said frame, the lower ends of the legs of said frame being formed with lateral extensions, and brackets detachably connected to the frame of the printing 15 press and provided with arms having cam-shaped openings therein to receive said extensions whereby in the movement of the platen toward the form, said frame will be elevated.

In testimony whereof I affix my signature.
CHARLES M. BRANDT.
